(57) **CLAIM**

The ornamental design for combined cap with a write-on surface and a writing implement holder, as shown and described.

DESCRIPTION

FIG. 1 is perspective view of an embodiment of a combined cap with a write-on surface and writing implement holder showing my new design in a closed position.

FIG. 2 is another perspective view of the cap in FIG. 1 in an open position.

FIG. 3 is a front view of the cap in FIG. 1.

FIG. 4 is a left view of the cap in FIG. 1.

FIG. 5 is a bottom view of the cap in FIG. 1.

FIG. 6 is a rear view of the cap in FIG. 1.

FIG. 7 is a right view of the cap in FIG. 1.

FIG. 8 is a top view of the cap in FIG. 1.

FIG. 9 is one perspective environmental view of the cap in FIG. 2 in an environment of use.

FIG. 10 is one perspective view of another embodiment of the combined cap with a write-on surface and writing implement holder in FIG. 1.

FIG. 11 is another perspective view of the cap in FIG. 10 in an open position.

FIG. 12 is a front view of the cap in FIG. 10.

FIG. 13 is a left view of the cap in FIG. 10.

FIG. 14 is a bottom view of the cap in FIG. 10.

FIG. 15 is a rear view of the cap in FIG. 10.

FIG. 16 is a right view of the cap in FIG. 10.

FIG. 17 is a top view of the cap in FIG. 10; and,

FIG. 18 is one perspective environmental view of the cap in FIG. 11 in an environment of use.

In the drawings, the broken lines showing portions of a cap, container and writing implement are for environmental purposes only and form no part of the claimed design.
